CLAIM

The ornamental design for an aerosol fire extinguisher,
as shown and described.

DESCRIPTION

FIG. 1 is a top, front perspective view of an aerosol fire extinguisher showing my new design;

FIG. 2 is a front elevational view thereof;

FIG. 3 is a top plan view thereof;

FIG. 4 is a side elevational view thereof, the opposite
side being a mirror image;

FIG. 5 is a rear elevational view thereof; and

FIG. 6 is a bottom plan view thereof.

FIGS. 1 and 2 show an actuator within the cap, the
actuator being hidden by a breakaway tab in FIGS. 3
and 5.
